DESIGN FOR A JAR

Lysle E. Adams, Chicago, Ill., assignor to Lysle E. Adams, as trustee

Application November 29, 1935, Serial No. 59,825

Term of patent 14 years

To all whom it may concern:

Be it known that I, Lysle E. Adams, a citizen of the United States, residing at Chicago, in the county of Cook and State of Illinois, have invented a new, original, and ornamental Design for a Jar, of which the following is a specification, reference being had to the accompanying drawing, forming part thereof and wherein

Fig. 1 is an elevational view of a jar showing my new design; and

Fig. 2 is a top plan view thereof.

I claim:

The ornamental design for a jar, as shown.

LYSLE E. ADAMS.
